UNITED STATES PATENT OFFICE.

WILLIAM C. BALES, OF COOLIDGE, GEORGIA.

RAILROAD JOINT AND CHAIR.

SPECIFICATION forming part of Letters Patent No. 741,440, dated October 13, 1903.

Application filed May 25, 1903. Serial No. 158,757. (No model.)

To all whom it may concern:

Be it known that I, WILLIAM C. BALES, a citizen of the United States, residing at Coolidge, in the county of Thomas and State of Georgia, have invented a new and useful Railroad Joint and Chair, of which the following is a specification.

This invention relates to the joints for uniting and supporting the adjacent abutting ends of railway-rails, and has for its object to simplify and improve devices of this character and produce a device which may be cheaply manufactured, easily and quickly applied, and which will securely support the rails and prevent displacement under the severest strains and concussions.

The invention consists in certain novel features of construction, as hereinafter shown and described, and specified in the claim.

In the drawings illustrative of the invention, in which corresponding parts are denoted by like designating characters, Figure 1 is a side elevation. Fig. 2 is a plan view. Fig. 3 is a transverse section on the line 3 3 of Fig. 1.

The improved joint may be applied to any of the various forms and sizes of rails manufactured and may be applied to rails with or without the usual spike-apertures in the base-flanges and clamp-bolt apertures in the vertical webs; but for the purpose of illustration the improvements are shown applied to rails having both the spike and clamp-bolt apertures above referred to.

The abutting rail ends are denoted at 10 11, with the usual transverse-spaced spike-apertures in the base-flanges and the transverse-spaced clamp-bolt apertures through the vertical webs, as indicated.

The improvement consists in two principal parts, a chair 12, extending beneath the rail ends and with one edge formed with an integral clamp-plate 13, embracing the base-flanges, and vertical webs at one side and likewise extended in advance of the rails at the other side and with the free edge turned over and overlapping the body of the chair, as at 14, and inclined to the plane of the rails, as shown in Fig. 2.

The vertical portion 13 of the chair is provided with spaced perforations corresponding to the clamp-bolt perforations in the ver-

tical webs through which the clamp-bolts 15 are adapted to pass when required.

The chair will likewise be provided with 55 spaced apertures 16, corresponding to the spike-recesses in the base-flanges, so that spikes may be driven through both parts into the ties 17, as represented.

The other principal part of the device consists of a member formed of a clamp-plate portion 18, adapted to engage the vertical webs and the base-flanges of the rails opposite to the portion 13 and with its outer edge 19 extended beneath the overlapping edge 65 14 and inclined to the plane of the rails, conforming to the incline of the turned-over edge 14, the plate 18 19 thus becoming a "wedge," which when driven into position very firmly clamps the parts together and ordinarily 70 needs no other fastening means. As a measure of security, however, a plurality of spike-apertures 20 are formed in alinement with spaced spike-apertures 21 in the adjacent portion of the chair 12, as indicated in Fig. 3, 75 the inner side walls of the apertures 20 being arranged in vertical alinement with the edges of the base-flanges on the side of the rails to which the wedge-shaped clamp-plate is applied in position to cause the heads of the 80 spikes to rest against and be braced by the edge of the chair-flange. By this means the inclined clamp-plate may be securely held and all danger of its working loose obviated, and in event of the parts becoming loosened 85 by wear or from other causes the joint may be tightened by removing the holding-spikes and driving the clamp-plate farther into the joint until the next pair of apertures "register." The clamp-plate 18 is also provided 90 with a plurality of apertures for the clamp-bolts 15, as shown in Fig. 1 for the same purpose, or so that the clamp-bolts may be adjusted simultaneously with the spikes in the apertures 20.

This makes a very simple, cheaply-constructed, and easily-applied joint, which will hold the rail ends very rigidly and which can be readily tightened in event of working loose.

Having thus described the invention, what I claim is—

A railway-rail joint comprising a chair adapted to enclasp the base-flanges of the

rails on one side and extending beneath the rails and beyond the base-flanges on the other side thereof with its free edge turned over to form a flange arranged in a plane above the body of the chair, a clamp-plate adapted to engage the vertical web of the other side of said rails and conforming in shape to the base-flanges thereof with its lower edge extended under said chair-flange, said plate having spike-apertures formed therein between the free edge of the chair-flange and the adjacent edges of the base-flanges of the rails, and

spikes disposed in said apertures with the heads thereof braced against the free edge of the chair-flange, and against the shanks of 15 which the base-flanges abut at their edges.

In testimony that I claim the foregoing as my own I have hereto affixed my signature in the presence of two witnesses.

WILLIAM C. BALES.
